UNITED STATES PATENT OFFICE.

EDWARD E. SMITH, OF PROVIDENCE, RHODE ISLAND.

WINDOW-TENSIONING DEVICE.

Application filed January 25, 1928. Serial No. 249,417.

This invention relates to a window tensioning device, and has for its object to provide in a window of the type in which the sash slides vertically in the frame, means for exerting a yielding tension between the sash and the frame to hold the sash against rattling.

A further object of the invention is the provision in such a vertically slidable window of a short length of tubing arranged to fit a bore in the side rail of the sash, a spring pressed plunger being mounted in the tubing to slidably press against the frame and so retain the sash against rattling while in any adjusted position in the frame.

With these and other objects in view, the invention consists of certain novel features of construction, as will be more fully described, and particularly pointed out in the appended claims.

In the accompanying drawings:

Fig. 1 is a side elevation showing a fragmental portion of the window sash mounted in a portion of a frame, the sash being partly in section showing my improved tensioning device mounted therein.

Fig. 2 is a sectional view showing a short section of tubing with an internal abutment formed therein.

Fig. 3 is a sectional view of the presser plunger.

Fig. 4 is a section on line 4-4 of the plunger.

Fig. 5 is a detail of the coil spring which exerts an outward pressure on the plunger.

Fig. 6 is a detail showing the screw which is to be threaded into the inner end of the plunger, the head being for the purpose of engaging the abutment and limiting the outward movement of the plunger.

Fig. 7 is a sectional view showing the removable parts with one end of the spring resting against one side of the abutment and the head of the screw engaging the other side of the abutment to restrict the outward movement of the presser plunger against action of the spring.

Fig. 8 is an enlarged sectional view showing the device as mounted in the side rail of the window sash and pressing against the surface of the window frame.

Fig. 9 is an edge view showing a portion of the window frame with portions of the upper and lower sashes mounted therein, the sashes being broken away showing my retainer mounted therein.

Fig. 10 is a perspective view of a window frame with a plurality of my retainers mounted therein.

It is found in practice that a large majority of the windows which slide vertically in a frame are sufficiently loose in the frame so that when partially opened the sash will shake and rattle in the frame when affected by action of a breeze of wind often to the great annoyance of the occupants of the room particularly when this rattling occurs during rest or sleeping hours; and to obviate this difficulty I have provided a very simple and inexpensive device which may be readily applied to the sash of a window by simply boring with a bit from its outer surface into the side rail and inserting into this bore the short length of tubing containing the spring pressed plunger so that when the window is again replaced in the sash the action of this presser between the frame and the sash will place the sash under tension and so effectually prevent the same from rattling; and the following is a detailed description of the present embodiment of my invention showing one arrangement of tensioning device by which these advantageous results may be accomplished:

With reference to the drawings, 10 designates the window frame in which the inner sash 11 is mounted to slide vertically between the inner casing strip 28 and the parting strip 27 and the outer sash 29 between the parting strip 27 and the outer casing strip 30, all of which serve as suitable bearing or guiding strips for the sashes. The edges of the side rail of each of the sashes are provided with spaced bores 12 in each of which a tensioning device 13 is mounted. This device is provided with a presser plunger member 14 to exert a sliding pressure, when in the inner sash 11, against the inner surface 15 of the parting strip 27 and when in the outer sash 29 to press against the inner face of the outer casing strip 30 to exert an inward pressure sufficient to make the sashes tight against leakage of air and also to prevent them from rattling in the frame. One form of tensioning device is herein shown which comprises a short length of tubing 16 in which a shoulder 17 is integrally formed by boring inwardly from the outer end 18 and then boring inwardly from the inner end 19 leaving a portion of the stock between the bores, which forms the shoulder 17 with the central opening 20. In

the outer end of this bore is fitted a presser plunger 21 which is preferably rounded on its outer end 22 to engage and slide in contact with portions of the window frame. 5 This plunger has a threaded bore 23 on its inner end for the reception of a limit screw 24.

In assembling these parts the coil spring 25 is dropped into the outer end of the tubing 16 with its inner end resting against 10 an abutment 17 and the presser plunger 21 is inserted to rest against the outer end of the spring.

In order to retain this plunger in position 15 against the spring and also limit its outward movement under action of the spring, the screw 24 is threaded into the threaded bore 23 of the plunger, the head 26 of the screw engaging the opposite side of the abutment 17 by which construction the plunger may be adjusted to limit the amount that 20 it shall extend out beyond the end 18 of its tubing. Also it will be noted that the combined length of the screw and the plunger 25 when assembled is less than the length of the tubing so that even when the plunger is pressed in so that its outer end is flush with the end of the tube, the head of the screw is then inside of the opposite end of the 30 tubing. By this construction it will be seen that it is only necessary to bore into the side rail of the sash and insert the tubing 16 with its plunger therein and when replacing the sash this plunger will slidably engage 35 the frame and retain the window under sufficient tension to prevent it from rattling.

It will be seen that by my improved construction of device that it may be set in any desired position in the frame either to press 40 sideways or inward or outward to engage the frame and prevent the window from rattling.

The foregoing description is directed solely towards the construction illustrated, but 45 I desire it to be understood that I reserve the privilege of resorting to all the mechanical changes to which the device is susceptible, the invention being defined and limited only by the terms of the appended 50 claims.

I claim:

1. In a window having a frame with inner and outer bearing strips for the edges of the

sash and a sash slidably in the frame between 55 said strips, a spring-pressed tension member comprising a tubular casing inserted into the edge of the sash having a spring pressed plunger mounted in said casing to engage its outer bearing strip and exert an inward pressure on the sash to make the window 60 tight and prevent the sash from rattling, and means for limiting the outward movement of the plunger in its casing.

2. In a window having a frame with inner and outer bearing strips for the edges of each 65 sash a sash slidably mounted between said strips, a tube having a spring pressed plunger therein and inserted into the edge of the sash to engage the outer bearing strip thereof and press the sash inward to make the 70 window tight and prevent the sash from rattling, a stop to limit the outward movement of the plunger in the tube, and an abutment for the spring and the stop intermediate the ends of the tube.

3. In combination with a window having inner and outer bearing strips, a tensioning device comprising a short length of tubing 75 fitting into a bore in the outer surface of the side rail of a window sash, said tubing having an abutment in its bore, a presser plunger at the outer end of the tube pressing outwardly against the inner surface of its bearing strip, a pressure spring acting between the abutment and plunger, and a 80 plunger stroke limit member connected to the plunger and having an enlargement to engage the opposite side of said abutment to limit the extending movement of said plunger.

4. A window tensioning device comprising a short length of tubing to fit a bore in the side rail of a window sash, said tube having an integral abutment in its bore, a 85 presser plunger at the outer end of the bore, a spring acting between the abutment and plunger to press the latter outwardly, a screw threaded into the inner end of the plunger and having a head to also engage the abutment to limit the outward movement 90 of the plunger, the combined length of the screw and plunger when assembled being less than the length of the tube.

In testimony whereof I affix my signature.

EDWARD E. SMITH.
